UNITED STATES PATENT OFFICE.

ADOLPHUS G. MEIER, OF ST. LOUIS, MISSOURI.

SAFETY DEPOSIT BOX.

Application filed December 30, 1925. Serial No. 78,291.

This invention pertains to safety deposit boxes or like containers for safe keeping of documents and similar articles.

Most banks make a practice of renting 5 safe deposit boxes at a certain sum per year in which valuable papers and other valuable articles may be kept. These boxes are kept in a suitable vault at the bank and carefully protected. In many cases, however, the pur- 10 chaser has only a few simple documents such as life insurance policies, property deeds, etc., which he wishes to protect against loss. The ordinary box as at present provided, is large enough to contain a 15 considerable number of such documents and consequently the yearly rental is comparatively high.

One of the objects of this invention is to provide a small and simple container which 20 may be rented at a low rental and which may, nevertheless, be adequately protected at a minimum cost.

Another object is to provide simple and effective means for sealing such a container.

25 Another object is to provide locking and sealing means for such a container which is adapted to receive the signature of the owner, which seal must be broken in order to open the container.

30 Further objects will appear from the following description taken in connection with the accompanying drawing, in which:

Figure 1 is a perspective view of a container embodying this invention.

35 Figure 2 is a section on line 2--2, Figure 1.

Figure 3 is a partial section on line 3--3, Figure 2.

40 Figure 4 is a perspective detail somewhat enlarged of the locking mechanism, and

Figure 5 is a perspective view of a key.

Referring to the accompanying drawing, 1 designates a container body which may be constructed of sheet steel or other suitable material and which is completely closed except at its forward end. The container is made flat and large enough to accommodate only a limited number of documents so that a considerable number of such containers may be stored in a small space. This 45 enables a great many of such containers to be stored in a given vault space and thereby reduces the cost of operating the system.

The forward end of the container may be 50 closed by a closure 2, comprising a plate adapted to fit the open front of the con-

tainer 1. Flanges 3 may be provided to fit within the container body and to properly position the closure. One end of the closure 2 is provided with a bracket 4 forming a 60 socket adapted to engage a pin 5, mounted at one side just within the opening of the container 1. Mounted in the other end of said opening is another pin or bar 6 adapted to provide an abutment for the locking bolt. 65

Mounted within the closure 2 and in the case illustrated, at one end thereof is a lock comprising a casing 7 suitably formed of sheet metal or the like and having slidably mounted therein a locking bolt 8. This 70 bolt is suitably guided to slide lengthwise in the casing 7, its movement being limited if desired by stop pins 9 and 10 adapted to engage the end of the casing. The bolt 8 is provided at an intermediate portion thereof 75 with rack teeth 11. Just opposite the rack portion 11, the closure is perforated with a keyhole 12. The keyhole 12 may be round or any other suitable shape adapted to accommodate the key 13. In the embodiment 80 illustrated this key is formed at its end to provide a pinion 14 adapted to engage the rack portion 11 of the bolt. The bolt 8 may be provided with a lug 15 to which a spring 85 16 may be attached, the other end of which is secured to a lug 17 on the casing 7. This spring automatically moves the bolt to the right, Figure 3, so that its end 18 will be extended from the casing to lodge behind the abutment 6 when the closure is in place 90 on the container so as to lock the closure to the container.

The lock casing 7 may be held in place on the closure 2 by bolts or other suitable fasteners 19. These bolts pass through the front of the closure 2 and may also be used to hold in place a keyhole plate 20 of fibre or other suitable material as illustrated in Figure 3. This plate covers that part of the closure in which the keyhole is situated and is itself provided with a keyhole registering with that in the closure 2.

In the use of this container, the articles to be preserved are placed within the container and the closure is then applied by first engaging the bracket 4 over the pin 5 and then swinging the closure inwardly until the bolt 8 lodges behind the abutment 6. When the container has thus been closed, a sticker 21 of paper or other suitable material upon which the owner has previously placed his signature as indicated in Figure 110

1, is then pasted on the keyhole plate 20 so as to cover not only the keyhole 12 but also the heads of the fasteners 19. This sticker provides a seal which must be broken 5 before the key can be inserted in the lock to open the container. When the owner desires access to the box, he applies to an attendant who provides him with a blank sticker upon which he signs his name. The 10 attendant then picks out his box by its number and after comparing the signature thereon with the signature on the new sticker, so as to be certain that the party applying is the proper owner of a box, delivers 15 the box to him. When the owner has ascertained that the original seal is still in place over the keyhole plate, the attendant may insert the key, breaking the seal, and open the box. When the box is again to be 20 sealed, it is closed in the regular manner and the new sticker pasted over the old one on the keyhole plate. Thus the container is always sealed by the owner's signature and the seal must be broken in order to open the 25 container.

The keyhole plate 20 is of special utility because such containers are ordinarily constructed of metal to which the adhesive of the ordinary stickers does not cling effectively, the keyhole plate of fibre or similar material to which the adhesive will cling permanently is desirable in order to insure that the seal will remain in place. If the box is opened frequently, an accumulation 30 of stickers will gradually build up thereon. When this takes place the attendant may, when the container is opened, remove the keyhole plate by removing the fasteners 19 and replace the same with a new one. A 35 supply of such plates may be kept on hand for the purpose. A renewable keyhole plate, therefore, provides that an unreasonable accumulation of stickers may be avoided by the removal and cleaning of such 40 plates periodically.

It will be seen, therefore, that this invention provides a simple container which is not only cheap to manufacture but which 45

takes up little space and which may, therefore, be rented at a very low rental so as to 50 be within the means of practically everyone and which will encourage the careful safe keeping of even one or two documents of value.

It is obvious that various changes may be 55 made in details of construction without departing from the spirit of this invention; it is, therefore, to be understood that this invention is not to be limited to the specific details shown and described.

Having thus described the invention, what is claimed is:

1. A container for safe keeping of documents and the like, comprising a box, a closure therefor, a key operated lock for said closure, a non-metallic sticker receiving key hole plate and a sticker adapted to adhere to said plate over the keyhole and puncturable by the key.

2. A container for safe keeping of documents and the like, comprising a box, a closure therefor, a key operated lock for said closure, a renewable sticker-receiving key hole plate for said lock and a sticker adapted to adhere to said plate over the keyhole and puncturable by the key.

3. A container for safe keeping of documents and the like, comprising a box, a closure therefor, a key operated lock for said closure, a renewable sticker-receiving key hole plate for said lock, means to fasten said plate to said closure and a sticker attachable to said plate for sealing the keyhole and said fastening means.

4. A container for safe keeping of documents and the like, comprising a box, a closure therefor, a key operated lock for said closure, a renewable sticker-receiving key hole plate for said lock, a screw passing therethrough to fasten said plate to said closure and a sticker attachable to said plate to cover the keyhole and the head of the screw.

In testimony whereof I affix my signature this 21st day of December, 1925.

ADOLPHUS G. MEIER.
